NONREFILLABLE BOTTLE

Samuel G. Conkling, Brooklyn, N. Y.

Application February 15, 1936, Serial No. 64,044

5 Claims. (Cl. 215—25)

This invention relates to new and useful improvements in non-refillable bottles, and it has for its object to provide a non-refillable bottle that will resist any attempt of refilling, and which may be depended upon to function infallibly in operation, or use.

The present device constitutes a further improvement of my invention in regard to non-refillable bottles for which the U. S. Patent, No. 2,013,726, has been granted to me, and for which I further have pending an application for patent, under Serial No. 753,833, filed Nov. 20, 1934, and it has for its special object to provide means in connection with a bottle of the kind described, whereby an even and quick flow may be obtained of the contents of said bottle, in regard to which still further constructural arrangement has been made, whereby the flow of liquid from the bottle may be adjusted and regulated.

As a still further improvement, the present construction has been made to embody a double action valve, or check, system, whereby any improper elimination of air from the body of the bottle, or the creation of a partial vacuum in the latter, as well as any improper filling of said bottle, even by forceful means, would be prevented.

As the construction of my invention, notwithstanding its meritorious features, is comparatively simple, the cost of manufacturing said bottle with my new, devised features embodied therein should be proportionately low.

With the above and other objects in view, this invention consists of the novel features of construction, combination and arrangement of parts, hereinafter fully described, claimed and illustrated in the accompanying drawing forming part of this specification, and in which similar characters of reference indicate corresponding parts in all views, and in which:—

Figure 1 is a vertical, transverse sectional view of my device.

Figure 2 is a side elevational view of same.

Figure 3 is a transverse sectional view, taken on the line 3—3 in Figure 2.

Figure 4 is a similar view, as Figure 3, taken on the line 4—4 in Figure 2; while

Figure 5 is a top plan view of a cork, or packing member; and

Figure 6 is a side elevational view of the valve.

Referring more particularly to the drawing, 10 indicates the body of a bottle, while 11 indicates the neck formed integral therewith; said neck is made with a rim therein, as indicated at 12.

55 In the neck portion 11 is seated a cartridge-

member 13, secured to the latter in any suitable manner, for instance, by means of a cementing process, as said cartridge-member is made to form an integral part with the neck. Above the cartridge-member suitable space may be left in the neck of the bottle for sealing the latter in the usual manner.

The cartridge-member comprises an upper section formed with an outlet, or bore, 14, therein, which bore may be of a straight, tortuous, or any suitable form. At the lower part of said section of the cartridge-member, and inside thereof, the latter is provided with a somewhat semi-spherical reduced portion, or chamber, 15, connecting with said bore, or passage, 14.

A roof 16, the form of which has been especially shown in Figure 3, is arranged in said upper section, a short distance below the bore 14; said roof 16 is formed with somewhat reduced side portions, as indicated at 17, in Figure 3, to permit suitable connection between the chamber 15 and the outlet 14 for the sake of passage of the liquid. The roof is integrally secured to the top 18 of said section by means of studs, or short legs 19, which legs are positioned close to the wall of the chamber; said roof, besides protecting the interior of the chamber 15, and somewhat regulating the fluid, also serves to limit the upward movement of the valve 20, hereinafter described.

The upper section of the cartridge-member has its sides made with slightly cut-out portions, or fine recesses 21, therein, while one of said cut-out portions 22 penetrates to the chamber 15. Said upper section has in its lower part been made with an outer annular recess 23, communicating with said cut-outs, 21 and 22.

In said recess 23, and in elongation of the cut-out portions 21, orifices 24, for the inlet of air, are formed in said recess, and penetrating to the chamber 15, as shown especially in Figure 4.

A valve 20 is arranged in the chamber 15, said valve is formed with a somewhat cup-shaped depending portion 25, as shown in Figure 6, and with an overlapping rim portion 26 adapted to engage the upper surface of a valve seat 27, while the arm 28 of said valve is positioned in and has as its fulcrum one of the said orifices 24, which latter orifice for this purpose is made slightly larger than the other orifices to accommodate the said arm, as shown at 29, in Figure 4.

The portion 30 of the cartridge-member below the recess 23 is at its lower end formed with a reduced portion 31, adapted to receive a cork, or packing member 32; said cartridge-member has its inner and lower portion of the valve seat 55

formed with a curved surface 33 adapted to receive therein a ball 34, when the bottle is in an inverted position.

It will from the above description of the construction appear that a perfect two-fold and double acting valve system has been attained, as a bottle with this improved device mounted therein, will be immune to any refilling in whatever form, or by whatever means attempted.

10 Thus in case, when the bottle has been emptied, attempt is made to refill the latter by trying to create a vacuum in the body of the bottle, the ball 34 would in this instance be drawn up close against its seat 33, as formed beneath the seat of the valve 20.

If, on the other hand, it is attempted to refill the bottle by a forced draft or blowing, or assuming, for argument's sake, that some vacuum has been created within the body of the bottle, the 20 valve 20 will assume its closed position, while the ball-valve 34 will be "shot" back upon its seat in the opening of the rim 12, thus preventing and double checking any attempted refilling of said bottle.

25 It is obvious that changes may be made in the form, construction and arrangement of the several parts, as shown and described herein, within the scope of the appended claims, without departing from the spirit of the invention, and I 30 do not therefore wish to limit myself to the exact construction and arrangement shown and described herein. What I claim as new and desire to secure by Letters Patent of the United States, is:—

35 1. In a device of the class described, a bottle having a body portion and a neck integral therewith, a cartridge-member mounted in said neck and made to form an integral part therewith, said cartridge-member having a chamber near 40 the bottom thereof and an outlet from said chamber, a valve formed with an arm and reciprocatingly arranged in said chamber, the cartridge-member being made with fine tube-like recesses therein, vertically arranged between the 45 outer surface of said cartridge-member and the neck of the bottle, one of said tube-like recesses penetrating to the chamber proper, said cartridge-member being upon the upper part thereof formed with an outer annular recess communicating with the aforesaid tube-like recesses, and orifices horizontally extending from said annular recess to the chamber and connecting indirectly 50 said vertical tube-like recesses with the latter, whereby to obtain an adequate air-inlet to facilitate the flow of the liquid in the bottle.

55 2. In a device of the class described, a bottle having a body portion and a neck integral therewith, said neck being formed with a shoulder inside thereof, a cartridge-member mounted in said neck and made to form an integral part therewith, said cartridge member having a chamber near the bottom thereof and an outlet from said chamber, a valve formed with an overlapping rim portion and having a short arm reciprocatingly arranged in said chamber, the cartridge-member being made with fine tube-like recesses 60 therein, vertically arranged between the outer surface of said cartridge-member and the neck 65 of the bottle, one of said tube-like recesses being substantially enlarged and adapted to receive the short arm of the valve therein.

of the bottle, one of said tube-like recesses penetrating to the chamber proper, said cartridge-member being upon the upper part thereof formed with an outer annular recess communicating with the aforesaid tube-like recesses, and orifices horizontally extending from said annular recess to the chamber and connecting said vertical tube-like recesses indirectly with the latter, one of said orifices being substantially enlarged and adapted to receive the short arm of the valve therein.

3. In a device of the class described, in combination, a bottle having a body portion and a neck integral therewith, said neck being formed with a shoulder inside thereof, a cartridge-member mounted in said neck and made to form an integral part therewith, said cartridge-member having a chamber near the bottom thereof and an outlet from said chamber, a valve formed with an overlapping rim portion and having a short arm reciprocatingly arranged in said chamber, the cartridge-member being made with fine tube-like recesses therein, vertically arranged between the outer surface of said cartridge-member and the neck of the bottle, one of said tube-like recesses penetrating to the chamber proper, said cartridge-member being upon the upper part thereof formed with an outer annular recess communicating with the aforesaid tube-like recesses, and orifices horizontally extending from said annular recess to the chamber and connecting indirectly said vertical tube-like recesses with the latter, one of said orifices being substantially enlarged and adapted to receive the short arm of the valve therein, and a ball loosely arranged in the neck of the bottle between the shoulder therein and the lower side of said valve seat and adapted to reciprocate between said shoulder and valve seat.

4. In a device of the class described, a bottle having a body and a neck portion, a cartridge-member mounted in said neck and made to form an integral part therewith, said cartridge-member having a chamber near the bottom thereof and an outlet from said chamber, the cartridge-member being made with fine tube-like recesses therein, vertically arranged between the outer surface of said cartridge-member and the neck of the bottle, one of said tube-like recesses penetrating to the chamber proper, said cartridge-member being upon the upper part thereof formed with an outer annular recess communicating with the aforesaid tube-like recesses, and orifices horizontally extending from said annular recess to the chamber and connecting said vertical tube-like recesses indirectly with the latter, one of said orifices being substantially enlarged, a valve seat at the bottom of the cartridge-member, a valve formed with an overlapping rim portion and having a short arm reciprocatingly arranged in said enlarged orifice, a roof arranged in the cartridge-member a short distance below the top thereof and being secured to the latter by means of studs positioned close to the wall of the chamber, substantially as and for the purpose set forth.

5. In a device, as claimed in claim 4, and where- 65 in said roof is formed with reduced side portions, substantially as and for the purpose set forth.

SAMUEL G. CONKLING.
